(57) **CLAIM**

We claim the ornamental design for a battery module, as shown and described.

DESCRIPTION

FIG. 1 is a perspective view of our new design for a battery module;

FIG. 2 is a front view thereof;

FIG. 3 is a rear view thereof;

FIG. 4 is a top view thereof;

FIG. 5 is bottom view thereof;

FIG. 6 is a right side view thereof; and,

FIG. 7 is a left side view thereof.

The broken lines in the drawings are for the purpose of illustrating unclaimed portions of the battery module and form no part of the claimed design.
